UNITED STATES PATENT OFFICE.

LESLIE R. N. CARVALHO, OF TOLEDO, OHIO.

CLOSURE DEVICE.

Application filed October 27, 1925. Serial No. 65,154.

My invention relates to closures for containers, such as tumblers, jars or similar containers, embodying certain features of and being in the nature of an improvement over the structure shown and described in the Carvalho Patents Numbers 1,413,256; 1,413,257; 1,413,653 and 1,413,654.

In the sealing operation, the metal covers or closures are commonly found displaced from their usual seats on the container, and, in many instances, a slight jar or accidental blow will knock the cap therefrom just prior to the act of sealing.

My invention relates to improvements in the construction of such closures, with a view to securing more certain seating of the closure upon the container top and the elimination of the accidental removal of said closure.

An object of my invention is to provide closure caps or covers with simple and useful means, available for use in the sealing operation to engage and grip the periphery of the container rim or top, should there arise, just prior to the sealing operation, an accidental jar capable of causing said closure cap to slide off.

A further object of the invention is to produce practical and simple means for removing the cap from the receptacle.

Other objects will appear hereinafter.

Reference being had now to the accompanying drawings forming a part of this specification:

Figure 1 is a sectional elevation of the container and closure.

Figure 2 is a fragmentary plan of the inner surface of the cap or closure.

Figure 3 is a fragmentary isometric view of the combined receptacle and closure, showing the operation of an implement for opening the receptacle.

Figure 4 is a side elevation of a receptacle and closure constructed in accordance with the principles of my invention.

Referring to the drawings for describing in detail the structure which is illustrated therein, a receptacle 5 is shown having tapered walls terminating at the upper extremity in a short vertical wall 9 having a lower vertical outer circumferential shoulder. A cover 6 constructed of any suitable material such as sheet metal or heavy waterproof cardboard, is shaped to provide a top portion 8 and a depending circumferential flange or skirt 10.

It will be noted that the top portion 8 is

depressed, leaving an outer annular edge 13 surrounding the depressed portion. A gasket 7 of cork or other suitable material is disposed within the top portion 8.

The marginal portion of the depending flange 10 is provided with a plurality of small tabs 11, for a purpose hereinafter to be described, disposed at regular intervals around the depending flange and produced by slitting the said flange. As will be seen from Figures 1 and 2, the sections of the margin between said tabs are inturned, forming a flexible concavo-convex annular flange, of an inner diameter a little less than the container 70 it is to fit. An object of the latter provision is to give the closure a tight peripheral gripping instrumentality around the container, when the former is seated upon the latter. The tabs 11 depend from the closure 6, as 75 shown in the drawings, and are curved in the same general direction as the closure, but with diminutive radii (Fig. 2).

In the assemblage of my closure over a container mouth, the cover 6 is thrust down upon the vertical face 9. The depressed part of the top 8 assists in seating the gasket to the best advantage. The resilient character of the upturned annular flange, it will be noted, accommodates the closure to any imperfection 85 in the manufacture of the container, as well as adapting the closure for further use in the dispensation of the contents of the container.

The depending tabs 11 serve an important purpose during the placing and sealing of the caps on the containers. When the cap is first placed on the container, and before it is engaged and forced down into position by a capping machine, it is supported with its in-turned flange 14 resting on the rim of the container. In this position, the tabs 11 depending below the lip prevent the cap from accidentally sliding out of position before it is forced down on the container by the capping machine. Obviously, there is left under each tab 11 a small recess between the wall 10 of the closure and the walls of the container. In the opening operation, any suitable implement, such as the tine of a fork, is inserted in the aforesaid recess under a tab 11 and the tab is thereby pried out and upward, causing an upward tearing 15 in the flange 10. The tabs 11 being convex are sufficiently rigid to permit such tearing of the flange. This tearing of the flange above the tab 11 weakens the structure somewhat and relinquishes the sealing pressure of the flange, so that the cap can

be easily removed, but at the same time is capable of reuse.

Modifications of the above may be resorted to within the spirit and scope of my invention.

What I claim is:

1. A receptacle closure comprising a top portion, a depending flange having a margin thereof formed at regular intervals with small lugs, said lugs being curved outwardly transversely of their length with diminutive radii to make tearing of said flange expeditious, and a resilient curved flange formed by bending inward the margin between the said lugs, to separably attach the closure to a receptacle by friction.

2. A receptacle closure having a marginal portion adapted to overlie an exterior portion of a receptacle, said marginal portion having a concavo-convex gripping means formed thereon by bending the said marginal portion inwardly and upwardly to provide an annular pocket, and a lip to yieldably and frictionally contact with the side surface of a receptacle, outwardly curved depending tabs of diminutive radii extending from said flange and making a recess between the container and the lower extremity of the closure for the insertion of a prying implement, whereby the said flange may be weakened and said cap expeditiously removed.

3. A receptacle closure comprising a top cover portion, a depending marginal flange,

and integral tabs arranged at intervals along said flange and extending downward therefrom, said tabs being outwardly convexed.

4. A receptacle closure formed of sheet material and comprising a top and a depending peripheral flange, the margin of said flange comprising inturned portions alternating with depending tabs, said tabs being curved about radii materially shorter than the radius of the said top to thereby stiffen the tabs and permit insertion of a prying implement.

5. The combination of a receptacle and a closure therefor, comprising a top cover portion formed with a slightly depressed area to project into the receptacle, a depending flange surrounding the receptacle, the lower margin of the flange having portions thereof curved inwardly and upwardly for yielding frictional engagement with the side surface of the receptacle, and integral tabs arranged between and adjoining said inturned portions, said tabs being extended below the inturned portions and spaced from the receptacle throughout their lengths prior to and during sealing of the receptacle, said tabs also being curved transversely about radii materially shorter than the radius of the top to thereby stiffen the tabs and permit insertion of a prying implement.

Signed at Toledo, in the county of Lucas and State of Ohio, this 22nd day of October, 1925.

LESLIE R. N. CARVALHO.
